DRAFT PROMOTER FOR FURNACES

Arthur A. Rea, La Grande, Oreg.

Application October 9, 1936, Serial No. 104,884

1 Claim. (Cl. 230—134)

This invention appertains to a blower for furnace constructions, and more particularly to a furnace of the hot air type.

The principal object of the invention is to provide a blower for a hot air furnace wherein means is provided for circulating the hot air under force.

Another important object of the invention is to provide a blower for a hot air furnace where-
10 in hot air can be delivered under force through the agency of means which will not cost much to install on conventional hot air furnaces.

These and various other important objects and advantages of the invention will become apparent to the reader of the following specification.

In the drawings:—

Figure 1 represents a top plan view of the furnace.

Fig. 2 represents a bottom plan view of the dome with the blower therein.

Fig. 3 represents a vertical sectional view through the furnace.

Fig. 4 represents a side elevational view of the rotor.

Fig. 5 represents a perspective view of the blade carrier of the rotor.

Fig. 6 represents a vertical sectional view through the rotor spider.

Referring to the drawings wherein like numerals designate like parts, it can be seen in Fig. 3, that numeral 5 represents generally a furnace which consists of the fire box 6, the ash box 7 and the heating drum 8. Spatially disposed around the furnace structure 5 is the shell 9 which has the air inlet conduit 10 at its lower end.

The top of the shell 9 is provided with the dome 11 which is provided with side wall portions 12 and a depending apron 13 which rests upon the upper edge of the shell 9. An inwardly curved flange 14 is provided on the inside of the apron 13 so as to direct warm air passing upwardly above the drum 8 toward the inverted conical shaped rotor 15 through the apex of which the shaft 16 is disposed. The shaft 16 extends downwardly through the dome 11 and is supported in this position by the bearing 17. Jamb nuts or the like 18 above and below the apex portion of the

rotor 15 serve to retain the rotor in proper position on the shaft.

The dome 11 is provided with outlets 19 to which pipes can be connected and through which air can be supplied to the various parts of a building.

As shown in Fig. 6, numeral 20 generally refers to a spider which consists of a plurality of radially disposed arms 21 radiating from a common central point 22 and are provided with suitable 10 openings 23 whereby the arms can be riveted to the bottom side of the conical-shaped rotor 15 so as to reinforce the same.

Elongated transversely curved blades 24 are secured to the bottom side of the rotor 15 and 15 these blades increase in thickness outwardly in proportion to the pitch of the rotor 15.

Thus it can be seen, that when the motor 25 which is located on the top of the dome 11 is started, the belt 26 which is driven by a pulley of the motor and is trained over the pulley 17 on the shaft 16, will drive the shaft 16 and rotor 15 so that the blades 24 will effect a pull and draw air upwardly through the shell 9 and force the same outwardly through the openings 19 into the various conduits of the hot air system.

While the foregoing specification sets forth the invention in specific terms, it is to be understood that numerous changes in the shape, size and materials may be resorted to without departing from the spirit and scope of the invention 30 as claimed hereinafter.

Having described the invention, what is claimed as new is:—

A draft promoter comprising a rotor, said rotor being of inverted conical shape, a frame structure having diverged arm portions, means for securing the frame to the bottom side of the rotor, blades secured to the bottom side of the rotor, said means for securing the frame to the rotor and also serving to secure the blades to the rotor, the central portion of the said frame crossing the apex portion of the rotor, a shaft provided with bearing means and having its lower ends secured both to the apex and central portions of the rotor and frame respectively, and means at the upper end of the shaft to rotate said rotor.

ARTHUR A. REA.
